MERCURY SWITCH RELAY

Carl H. Larsen, Elkhart, Ind., assignor to The
Adlake Company, a corporation of Illinois

Application November 24, 1941, Serial No. 429,213

14 Claims. (Cl. 200—112)

1

This application is a continuation-in-part of application, Serial No. 335,659, now Patent No. 2,303,371, dated December 1, 1942, entitled Mercury switch relay.

At present mercury switches of the displacer type cannot generally be manufactured by the so-called mass production methods, as many of the essential parts of these switches are of glass which cannot be easily formed to exact dimensions. Because of this the various assembled units going to make up the switch cannot be prepared independently as sub-assemblies and later assembled, with any assurance that the operating characteristics of the finished switches will be within permissible tolerances. The use of glass as an envelope material has other limitations; for example, a high pressure gas fill cannot be safely used, and there are several applications in which switches having a glass envelope cannot be employed due to the possibility of breakage by excessive vibration or accidental blows.

An important object of my invention is, therefore, to provide a shock resistant displacer type mercury switch formed of materials which may be readily shaped within close dimensional tolerances.

Other objects are to provide a switch having a high breakdown potential and low contact resistance capable of functioning as either a front or back contact switch, according to its position; to provide a displacer switch with a non-magnetic metal envelope having external means of adjusting an internal time delay; to provide a switch composed of sub-assemblies which are interchangeable with corresponding parts of similar switches of like design; to provide improved mercury displacing means for use in mercury switches having metallic envelopes; to provide a relay highly resistant to accidental damage and short circuiting; and to provide improved means of joining together these sub-assemblies.

Other objects and advantages will become apparent from the description and drawings, in which

Fig. 1 is a vertical sectional view of my improved mercury switch positioned to operate as a front contact switch;

Fig. 2 is a vertical sectional view of the same switch positioned to operate as a back contact switch;

Fig. 3 illustrates a modified form of my switch, incorporating a time delay element;

Fig. 4 is a diagrammatic view of an apparatus suitable for use in filling my switch with gas;

2

Fig. 5 illustrates another form of my invention, incorporating a modified switch envelope;

Fig. 6 is a sectional view of a reversible time delay element in an upright position; and

Fig. 7 is a sectional view of the same time delay element in an inverted position.

Referring to Fig. 1, the switch envelope 11 is tubular in form, and has a uniform external diameter. The interior is polished to decrease friction, and counterbored at each end, as shown at 13, to form an internal shoulder 14. The envelope consists of a non-magnetic metal which will not amalgamate or otherwise harmfully combine with mercury, and which is capable of being machined or formed within reasonably close dimensional tolerances.

Because of their high strength, ready availability, and other desirable properties, I prefer to use ferrous alloys in forming my switch envelope, and I have found that steel properly alloyed with sufficient amounts of manganese or chromium and nickel, or combinations thereof, have suitable non-magnetic properties. The non-magnetic properties of these alloys is believed to be due to the action of the alloying ingredients, which act to hold the iron in the form of austenite during the cooling process—austenite being the non-magnetic form of iron. An example of such an alloy is stainless steel having an approximate composition of 18 per cent chromium and 8 per cent nickel (generally termed "18-8 steel"). I have found that this particular steel is well suited for use as an envelope material, particularly as it is both non-magnetic and resistant to wetting by mercury.

Another example is the steel known as "Hastfield" steel, one of the best known examples of which has about 12.5-13% manganese, 1.05-1.2% carbon, and 4-8% silicon. Any other manganese steel having therein sufficient manganese (at least 9 or 10%) to maintain the steel in its austenitic form as it cools to the lower atmospheric temperatures can be used. However, no metal readily amalgamating with mercury should be used in sufficient proportions in any steel that is in contact with mercury to amalgamate appreciably under the conditions of use unless alloyed in such form as to prevent substantial amalgamation. Except for cost, tungsten or molybdenum could be used for the switch envelope inasmuch as each is both non-magnetic and non-amalgamating. Any other non-magnetic metal, such, for example, as brass, could be used, if plated on its inner side with chromium, or other metal which will not amalgamate under conditions encountered.

The non-amalgamating metal used in this plating may even be magnetic, as iron, provided the plating is of such thinness that the tubular envelope as a whole is substantially non-magnetic.

A specific steel of the general type known as 18-8 is Carpenter stainless steel No. 4, having a composition (beside iron) of chromium 18%, nickel 9%, and carbon .08-.1%. For commercial reasons this is probably the most desirable at the present time. The following description will, therefore, be confined to the use of this material, although it is to be understood that other alloys having similar non-magnetic and non-amalgamating properties may be substituted if desired.

It is important that the metal chosen for the switch envelope be essentially non-magnetic. A magnetically responsive displacer 33 moves within the switch to change the mercury level, and if the envelope is of magnetic material the displacer may be held to the envelope by the magnetic force employed to actuate the switch or the residual magnetism resulting therefrom. As the functioning of the switch depends upon the movement of the displacer, it is apparent that any force preventing such movement will also prevent the functioning of the switch, and as substantially no air gap exists between the displacer and the envelope even a slight magnetic force in the envelope may have undesirable effects. Furthermore, the magnetic actuating force would be shunted away from the displacer by a magnetic envelope.

A cap, generally designated 15, consists of a metallic disk 16, adapted to be received in the counterbore 13 and to fit snugly against the internal shoulders 14. An opening is provided in the disk 16, to which is welded, or otherwise attached, a small metal tube 17. The thickness of the disk 16 is somewhat less than the depth of the counterbore 13, so that when the disk 16 is inserted within the counterbore against the shoulders 14 portions 18 of the envelope 11 will extend beyond the outer surface of the disk.

When it is desired to seal the cap 15 to the switch envelope 11 the cap is inserted, as described, against the internal shoulders 14, and the projecting portions 18 of the envelope are turned inwardly against the exterior portion of the disk 16, thereby pressing the disk firmly against the shoulders 14. The joint between the turned-down portion 18 of the envelope 11 and the outer surface of the disk 16 is subsequently sealed with hard solder, as indicated at 19, or by other suitable material, to form a strong gas-tight joint. The disk may also be welded in place, if desired, and it may be of any suitable metal not amalgamating with mercury, as stainless steel, ordinary iron, or a metal known in the trade as "Kovar."

A base 21 consists of a disk of metal adapted to be received in the counterbore 13, in a manner similar to that described in connection with the cap 15, and is provided with an opening 22 in which an electrode 23 may be positioned. The disk 21 is formed of a metal having a coefficient of thermal expansion substantially equal to that of hard glass and molybdenum. A metal having these characteristics is commercially available under the trade name of "Kovar," and consists essentially of an alloy of iron, cobalt and nickel.

The electrode 23 is preferably of molybdenum, and is covered for a portion of its length by insulating sleeve 24 of hard glass, such as Corning G-705 AJ, which has a coefficient of thermal

expansion substantially equal to that of molybdenum and "Kovar." The insulating sleeve 24 is preferably heat bonded to the electrode 23. The electrode 23 and the insulating sleeve 24 are positioned within the opening 22 in the base 21 by forming bulges or shoulders 26 in the insulating sleeve, adjacent to both sides of the opening 22, and subsequently applying sufficient heat to cause the glass to bond to the base 21. This forms a strong gas-tight seal, as the electrode, the glass and the base all have approximately the same coefficient of thermal expansion.

The insulating sleeve 24 surrounding the electrode 23 extends into the switch envelope 11 for slightly less than half the distance between the base 21 and the cap 15, and serves to insulate the electrode from contact with the base 21 and the mercury fill, except for a portion 27 of the electrode which extends beyond the insulating sleeve. The upper end of the sleeve 24 has a shoulder 28 formed integrally therewith, and fused to this shoulder is a ceramic tube 29, formed of a material, such as "Alundum," which has substantially the same coefficient of thermal expansion as the glass. The shoulder 28 is generally circular in section, but is formed eccentrically with respect to the electrode 23, so that the exposed portion 27 of the electrode will be close to one side of the ceramic tube 29 after assembly. The upper end of the ceramic tube 29 is closed with a glass seal 31, and an opening 32 is provided through the side wall of the tube 29 approximately midway between the top and bottom thereof, and at a point furthest removed from the eccentrically positioned electrode 23. The exposed portion 27 of the electrode 23 extends into the tube 29, and terminates adjacent to the glass seal 31.

I prefer to form the entire electrode structure separately from the balance of the switch, and to seal this sub-assembly into the switch envelope in a manner similar to that described in connection with the cap 15.

The displacer, generally designated 33, is telescoped over the electrode assembly, and may consist of a tube 34 of magnetic material, such as iron, telescoped over a sleeve 36 of insulating material, such as glass, the latter sleeve being somewhat longer than the tube 34. The ends of the iron tube 34 are reduced in external diameter, forming an external shoulder 37. Guide washers 12 are fitted over the insulating sleeve 36 and the reduced portion of the iron tube 34 against the external shoulders 37, and may be of the type described in my Patent No. 2,060,811. These washers serve to prevent any appreciable sideward movement of the displacer assembly 33 by contact with the inner walls of the switch envelope 11.

Coil springs 38 are fitted over the projecting ends of the interior insulating sleeve 36, and frictionally engage said sleeve to maintain the component parts of the displacer assembly 33 in their proper relation. These springs are of non-magnetic material, and serve to prevent the sticking of the displacer to either the cap 15 or the base 21, and are particularly necessary when the cap 15 is formed of a magnetic material, such as iron.

As the switch envelope 11 serves as one of the electrodes of the switch, it is often desirable, but not essential, to provide means of insulating the envelope 11 from other adjacent external portions of the switch assembly, and from accidental contact or short circuiting. This may be conveniently accomplished by mounting the assembled switch mechanism within a rigid tube

39, having a length somewhat greater than that of the switch mechanism. The tube 39 may be suitably formed of an insulating material, such as Bakelite, and the switch assembly held within the tube by applying a suitable sealing material, such as sealing wax, to the ends of the tube after the switch mechanism is positioned therein, as indicated at 41.

If the switch assembly is to be mounted within an insulating tube, it is necessary to provide means of forming a connection with the electrodes, viz. the switch envelope 11 and the centrally positioned electrode 23. This may be accomplished by attaching a connecting wire 42 to the switch envelope at any desired point, the wire being of sufficient length to extend beyond the tube 39. Electrode 23 may also be joined with a connecting wire in a similar manner, or extended beyond the tube. Connecting wires of this nature may be attached to the switch when the tube 39 is not employed.

A coil 43, having an iron circuit 44, is provided with an opening in which the switch assembly is positioned. Pole sleeves 46 may be provided fitting around the tube 39 and in contact with the iron circuit 44 to define an air gap 47. If the coil is to be energized by an alternating current, the pole sleeves 46, or the iron circuit 44, or both, may be split to overcome the undesirable magnetic effects of such current, as high eddy current loss. This split need not extend completely across the iron circuit, but may be positioned on the portions lying above and below the coil 43, extending from one edge of the iron circuit 44 to the opening in which the switch envelope is positioned. The split in the pole sleeves should be axial, and sufficient in width to prevent contact of the edges of the sleeve when positioned around the switch. The magnetic portion 34 of the displacer 33 may also be split in a similar manner.

The pole sleeves 46 are not essential, but are desirable, as they render the switch more sensitive to small exciting currents in the coil, and the action of the displacer 33 in response to the coil may be controlled within certain limits by adjusting the position of the air gap 47.

The switch may be conveniently maintained in position within the coil 43 by means of a rubber sleeve 48, frictionally engaging the insulating tube 39, or the switch envelope 11 if the insulating tube is not employed. The sleeve 48 is cylindrical in form and has a central opening of a diameter slightly less than the external diameter of the tube 39 or the switch envelope 11. The upper portion of the sleeve 48 is reduced in diameter to receive a bracket 49, of rigid material, which is adjustably secured to the iron circuit 44 by means of a machine screw 51. The external diameter of the lower portion of the rubber sleeve 48 is greater than the diameter of the opening in the coil 43, so that the switch is prevented from moving downwardly by the frictional engagement of the sleeve 48 with the tube 39. Upward movement of the switch assembly is prevented by the bracket 49, which may also be used to deform the rubber sleeve 48 into firmer contact with the tube 39 or with the switch envelope 11, as the case may be. Other types of switch mountings may be used, but I have found the type described advantageous because of the ease with which the position of the switch within the coil may be adjusted.

The switch envelope 11 contains a quantity of mercury 52, and is filled with an inert gas, or

mixture of such gases, belonging to the class comprising helium, hydrogen, nitrogen, argon, or helium hydride. The gas fill is admitted to the switch through the small tube 17 sealed to the disk 16, the opening of the tube 17 communicating with the interior of the switch. When the desired amount of gas has been admitted to the switch envelope the tube 17 is closed in a suitable manner, as by pinching and welding, indicated at 53. The gas fill may be of any desired pressure, either above or below that of the atmosphere, but I prefer to use relatively high pressures, on the order of 100 pounds to the square inch, as I have found that inert gas, particularly hydrogen at these pressures, has the property of quickly quenching any arc formed when the circuit through the electrodes is made or broken, and gives a higher break-down potential. In certain instances even higher pressures may be employed, as the efficiency of the inert gas in quenching the arc increases with its pressure.

The displacer 33 floats on mercury fill 52 when the coil is deenergized, the amount of mercury in the envelope 11 being such that when the displacer 33 is in its deenergized position the level of the mercury will be approximately half way between the base 21 and the cap 15. This is below the level which may be called the contact level of the electrode 23; i. e., the level to which the mercury must rise to complete the circuit. The opening 32 of the ceramic cup 29 determines the contact level in the illustrated form, and is above the low level of the mercury when the switch is upright, so that when the displacer 33 is in its deenergized position there is no electrical contact between the electrode 23 and the switch envelope 11. The ceramic sleeve 29 forms a cup around the exposed portion 21 of the electrode 23, and in operation will always retain a certain amount of mercury in constant contact with the exposed portion of the electrode.

The air gap 47 is positioned somewhat below the displacer 33. When the coil is energized the displacer 33 is drawn downwardly, causing the mercury to rise within the envelope 11 and contact the pool of mercury remaining within the sleeve 29 through the opening 32, thereby completing the circuit between the electrode 23 and the switch envelope 11. When the coil 43 is deenergized the displacer 33 will rise, due to its own buoyancy, causing the mercury level to fall within the envelope and break the contact between the electrode and the switch envelope.

The type of switch above described is generally known as a front contact switch, that is, a switch in which the circuit through the electrodes is normally incomplete when the controlling coil is deenergized. This switch may be converted into a back contact switch, wherein the circuit through the electrodes is complete when the coil is deenergized, and broken when energized by simply inverting the entire switch assembly. When the switch is inverted the parts will assume the positions shown in Fig. 2, wherein the mercury level, with the displacer 33 in its deenergized position, lies above the opening 32 in the ceramic sleeve 29, and the air gap 47 is positioned above the displacer 33. When the switch is in this position and the coil 43 is energized, the displacer 33 will be drawn upwardly, causing the mercury level to fall and break the contact between the electrode 23 and the switch envelope 11 through the opening 32.

Whether the switch is upright or inverted, the making or breaking of the circuit is always be-

tween mercury and mercury, for in the inverted position the ceramic sleeve 29 and the glass seal 31 also form a cup which retains a certain amount of mercury in constant contact with the exposed portion 27 of the electrode 23, regardless of the position of the displacer. The material from which the sleeve 29 is formed is also sufficiently porous to prevent entrapment of gas.

I have described in detail the method of forming my switch to obtain a front contact in the upright position and a back contact in the inverted position. By adjusting the mercury level, the position of the air gap 47 and the size and/or position of the opening 32, I may provide a switch functioning as front contact in either the upright or inverted positions, or as a back contact in either position.

It should be noted that the height of the mercury with respect to the base 21 in Fig. 1 is not necessarily the same as the height of the mercury with respect to the cap 15 in Fig. 2, as the insulating electrode sleeve 24 and the electrode assembly displaces a certain amount of mercury. Therefore, unless correction is made, the normal height of the mercury within the switch envelope, when the switch is in its upright position, will be greater than when the switch is in its inverted position, as shown in Fig. 2. This level may be adjusted by providing means of artificial displacement adapted to be covered with mercury when the switch is in its inverted position, as shown in Fig. 2. This may be suitably accomplished by enlarging the volume of the glass seal 31 to provide a displacement equivalent to that produced by the electrode assembly and insulating sleeve 24.

To provide a switch functioning as a back contact switch in either position, I may, for example, enlarge the diameter of the opening 32 in the sleeve 29, so that in its upright position the level of the mercury will be above the lower margin of this opening. If necessary, I also increase the volume of the glass seal 31, so that in its inverted position the level of the mercury will also be above the opening 32. The position of the displacer 33, with respect to the air gap 47 is then altered by moving the switch envelope within the coil to a point where the air gap lies above the normal position of the displacer, so that when the coil 43 is energized the displacer 33 will be drawn upwardly, causing the level of the mercury to fall and break the normally existing electrical contact between the electrode 23 and the mercury fill 52. The switch will function in the same manner in the inverted position, the position of the switch within the coil being altered, however, in each case, so that the air gap 47 will be above the displacer.

My switch may be made to function as a front contact switch in either position by forming the opening 32 in the sleeve 29 at a point substantially half way between the cap 15 and the base 21, and adjusting the mercury level to a point normally below this opening in either position. In this modification, the air gap must be positioned below the normal level of the displacer, so that movement of the displacer in response to the coil 43 will be downwardly, causing the level of the mercury to rise and complete the contact between the mercury fill 52 and the electrode 23.

It may be seen, therefore, that by very minor adjustments I may obtain extreme flexibility in operation, and may provide a switch operating as a front contact when in one position and

as a back contact when inverted, or as a front contact in either position, or as a back contact in either position. There are, of course, methods other than that described of controlling the operating characteristics, as the function of the switch depends upon the disposition of the opening 32 with respect to the mercury level. Broadly, if the switch is to function in the same manner, whether upright or inverted, the opening 32 should be substantially midway between the cap and the base, and the height of the mercury above the base in an upright position, substantially equal to the height of the mercury above the cap in an inverted position.

If, on the other hand, the switch is to function as a front contact switch in one position and as a back contact switch when inverted, the opening 32 will be positioned above the normal mercury level with the switch in one position, and below the normal level when inverted. In each case, it is understood that the direction and extent of movement of the displacer is such as to cause movement of the mercury fill to change the condition of the circuit between the mercury and the electrode 23, and that the direction and extent of this movement may be controlled by changing the position of the switch envelope, and hence the displacer, with respect to the air gap 47 in the iron circuit 44.

Due to the large area of the foot electrode or switch envelope 11, the contact resistance of my switch is extremely low, thereby making it efficient to operate. The switch is also highly resistant to damage by accidental blows, and may therefore be used under circumstances which would prohibit the use of a switch having a glass envelope.

Fig. 3 illustrates a modified form of my invention incorporating a time delay element, generally designated 54. The envelope 11 is the same as that described in connection with Fig. 1, as is the base 21 and the lower portion of the electrode assembly. The cap, generally designated 56, is cylindrical in form, and is provided with an outwardly extending end flange 57, which is proportioned to be received in the counterbore 13 in the end of the envelope 11. The thickness of the flange 57 is somewhat less than the depth of the counterbore 13, so that when the cap 56 is inserted in the end of the envelope it will fit tightly against the shoulder 14, and may be attached to the envelope in a manner similar to that described in connection with Fig. 1. The cap 56 is provided with an axial opening 58, communicating with the interior of the switch envelope. A lateral opening 49 is also provided intercepting the axial opening 58, and proportioned to receive a tapered plug or stop cock 61 containing a transverse opening 62, adapted to register, when in one position, with the opening 58, and when turned ninety (90) degrees therefrom to close said opening. The upper portion of the cap is somewhat reduced in external diameter and is provided with external threads, as indicated at 63.

In this modification the insulating electrode sleeve 24 is formed with a larger external diameter, and extends upwardly to a point somewhat below the low mercury level, where the diameter of the insulating sleeve 24 is enlarged to form a shoulder 64, to which is fused a gas impervious thimble 66 of a material such as glass. The electrode 23 extends upwardly beyond the shoulder 64 within the thimble 66, and is insulated for

a portion of its length by an extension 67 of the insulating sleeve 24. This extension 67 also has a shoulder 68 formed upon its upper portion, to which a small ceramic sleeve 69 of Alundum, or other suitable ceramic material having a coefficient of thermal expansion substantially equal to that of the glass, is fused. This sleeve 69 fits around the exposed portion 27 of the electrode 23, forming a cup in which a small pool of mercury is retained. If desired, the sides of this sleeve 69 may be truncated.

An opening 71 is provided in the side of the thimble 66, the diameter and position of the opening being such that the upper portion thereof is below the lip of the small ceramic cup 69. Another opening 72 is provided in the upper portion of the thimble 66, adapted to receive a plug 73 of porous material, through which gas may pass.

The displacer, in this instance, comprises a tube 74 of magnetic material, such as iron, having its external diameter reduced at each end to form an external shoulder 76. Guide washers 12 are fitted over the ends of the displacer and against the external shoulder 76. Portions of the tube 74 extend beyond the shoulder 76 and the guide washers 12, which may be bent sharply outwardly, after the guide washers have been placed in position, to hold the washers in place, and then bent inwardly at an angle, forming legs 77, substantially as shown. These legs 77 serve to prevent any sticking of the displacer to the cap 56 or the base 21.

The coil 43 and the iron circuit 44 are similar to those described in connection with Fig. 1, but in place of the rigid tube 39 sleeves 78, of insulating material, may be interposed between the pole pieces 45 and the switch envelope 11, to insulate the iron circuit 44. The switch may be supported in the same manner as that previously described, with the rubber sleeve 48 in direct contact with the switch envelope 11.

Mercury is added to the envelope 11 and the assembled switch connected with any suitable filling apparatus. In filling these switches with gas, particularly those incorporating a time delay element, I prefer to use an apparatus similar to that described in my Patent No. 1,967,949, illustrated diagrammatically in Fig. 4. This apparatus may consist of a pipe line 79, having a pressure gauge 80, a high frequency discharge device 81 connected to the pipe line through a valve 85, a three-way stop cock 82, a vacuum pump 83, and a source 84 of inert gas having a control valve 86. The gas supply 84 and the vacuum pump 83 are connected with the pipe line 79 through the stop cock 82. All parts of the system are preferably of metal with the exception of the extension 87, containing the electrode of the high frequency discharge device 81, which is of glass.

Nipples 88, or other suitable connecting means, are provided on the pipe line 79, by means of which the switches may be attached and are, in this case, threaded to cooperate with the threaded portion 89 of the cap 56. When the switches have been attached to the pipe line 79, substantially as shown, the stop cock 61 in the cap 56 is turned to the open position, in which the transverse opening 62 registers with the axial opening 58, thereby allowing communication with the interior of the switch envelope. The stop cock 82 is turned to a position cutting off the gas supply and connecting the pipe line 79 with the vacuum pump 83. Air is exhausted from the interior of the switch envelope, the degree of vacuum being

gauged by the appearance of the high frequency discharge, or, if desired, by means of a suitable gauge, not shown. During this process the valve 85 is open, allowing communication between the extension 87 and the pipe line 79. When the desired degree of vacuum has been obtained, valve 85 is closed and the position of the stop cock 82 changed to disconnect the vacuum pump from the pipe line 79 and to connect the gas supply 84. The valve 86 is opened and gas is allowed to fill the switches.

This operation is repeated several times to insure the complete removal of all air, and in the final operation gas is admitted to the desired pressure and the stop cock 82 turned to a position disconnecting both the pump 83 and the gas supply 84 from the pipe line 79. The stop cock 61 in the valve cap 56 is turned to the "off" position, thereby effectively sealing the switch envelope 11. 15 If desired, switches may now be connected to a suitable testing circuit and their operating characteristics determined without removal from the filling apparatus.

It is, of course, obvious that the action of the 25 time delay element will be governed largely by the density of the gas within the envelope 11, and the time delay characteristics, may, therefore, be conveniently varied by adjusting the gas pressure either while the switch envelope is connected to the filling apparatus or after it has been removed. When the desired characteristics have been obtained, the switch is removed from the apparatus and the cap 56 dipped in hard solder, indicated at 89, completely covering the exposed portion of 30 the cap 56.

The time delay element 54 is simply illustrative of one of the many types which may be incorporated in my invention, and operates in the following manner: When the coil 43, surrounding 40 the switch, is energized the displacer 74 is drawn downwardly into the mercury, causing the mercury within the envelope 11 to rise rapidly until it reaches the upper limit of the opening 71. The mercury outside of the thimble 66 will continue 45 to rise rapidly, but as a certain amount of gas is trapped by the mercury within the thimble the rise of the mercury therein is delayed until a sufficient amount of the entrapped gas has escaped through the porous plug 73, allowing the mercury within the thimble 66 to rise to the lip of the interior ceramic cup 69 and complete the circuit between the switch envelope 11 and the electrode 23. When the coil 43 is deenergized the displacer 74 will rise rapidly, due to its own buoyancy, causing the mercury outside of the thimble 66 to fall. The mercury remaining within the thimble, however, does not fall rapidly until the level of the mercury outside of the thimble has fallen below the upper portion of the opening 71, 55 at which time the mercury column remaining within the thimble is undermined and the circuit abruptly broken. This type of time delay element provides a delayed make, but it is obvious that by modifying the construction other types 60 of time delay action may be secured.

The type of envelope shown in Fig. 3 is interchangeable with the type illustrated in Figs. 1 and 2; that is, its capacity internal and external diameter and counterbore are equal. The cap 15, 70 illustrated in Fig. 1, and the displacer 33 are also interchangeable with the cap 56 and the displacer 74 described in connection with Fig. 3. The electrode base 21 is also standardized to receive any one of several possible types of electrode assemblies, including those having various time delay

functions, and to fit any of the various forms of switch envelopes. In my switch it is practical to provide for the interchangeability of parts as described, because the portions of the switch having critical dimensions are of metal which may be readily formed within close dimensional tolerances.

The advantages accruing from this type of construction are obvious. For example, I may form several sub-assemblies, consisting of the base, electrode structure and time delay element, each having different predetermined operating characteristics. When a switch having certain characteristics is required the sub-assembly having these characteristics is chosen and simply attached to the standardized envelope, together with the other necessary parts. The assembled switch will have the desired characteristics, as all portions of the switch affecting its operating characteristics may be accurately controlled, and testing may be eliminated except for occasional check tests. It would be impractical, from a manufacturing viewpoint, to form interchangeable sub-assemblies from glass, as the parts could not be economically formed within sufficiently close dimensional tolerances.

As previously mentioned it is possible, within certain limits, to control the action of the time delay element 54 by the pressure of inert gas within the envelope 11. If it is necessary to alter the characteristics of the switch after assembly the stop cock 61 may be carefully turned toward the open position, allowing a small quantity of the gas within the envelope to escape, until the desired operating characteristics have been obtained.

Fig. 5 illustrates particularly a modified form of switch envelope 11, in which the envelope is formed in the shape of an elongated cup. The counterbore 13 at the open end of this envelope, as well as the internal and external diameters and the capacity, are the same as those previously described. An opening 91 is provided in the closed end of the envelope, to which the small tube 17, similar to that described in Fig. 1, may be attached by welding or otherwise. This tube may also be sealed in a similar manner. The remaining parts of the switch are similar to those described in Fig. 3, with the exception of the electrode structure, which is shown in its simplest form, comprising the insulating sleeve 24 having a shoulder 68 upon its upper end, to which is attached the small ceramic cup 59 surrounding the bared end of the electrode 23. The switch operates in a manner similar to that previously described.

This particular type of switch envelope possesses certain advantages, particularly in respect to the strength of the envelope, as it may be seen that one of the seals, viz: that formed between the cap and the envelope, is eliminated by this type of envelope. This feature is important in my switch, for, as previously mentioned, I prefer to use high gas pressures, and the envelope must, therefore, be sufficiently strong to safely retain the gas, and the omission of one seal avoids that source of possible defect in the seal.

The resistance to wetting, by mercury, of the metals referred to for envelope 11 and the disks 15 and 21 seems to be advantageous in connection with the seals. With such metals the mercury is unable to penetrate between the envelope 11 and the disk 21 to reach the solder 19 with which it might amalgamate. At present, non-

amalgamating metals are also non-wetting. Of course, if a non-amalgamating metal, which is wet by mercury under the conditions encountered, were found, and the illustrated seal were found unsafe, a different seal could be used. However, at present the non-wetting characteristic, as well as the non-amalgamating, is desired for best operation of the switch.

For the utmost dependability in the seal the junction between disk 21 and envelope 11 should be exposed to the gas fill before this junction is subjected to contact with the mercury at high pressure. If there are any small clearances, the non-wetting characteristics of the metal will have kept the mercury out of the clearances at low pressure, and the entrapment of the gas will dependably keep the mercury away from the solder on the outside of the seal, even at high pressure. As a matter of fact, there will rarely be any clearances, especially if the projecting portion of the envelope 11 is upset and pressed against the disk 21 with considerable pressure, as in a press.

The time delay device 54, described in connection with Fig. 3, is, of course, adapted to operate only in an upright position. Figs. 6 and 7 illustrate a time delay element operable in either an upright or inverted position, and adapted for use in any one of the various modifications of my invention hereinbefore described.

Fig. 6 illustrates my reversible time delay element in its upright position. The element comprises a sleeve 102 of insulating material, such as glass or ceramic, attached to a shoulder 101 formed integrally with the insulating sleeve 24, and is closed at the top by a glass seal 103. The electrode 23 is positioned eccentrically with respect to the sleeve 102 and extends into said sleeve, terminating adjacent to the glass seal 103. The lower portion of the electrode within the sleeve 102 is insulated by an extension 104 of the insulating sleeve 24, the end portion of the electrode also being insulated by a cup 106 telescoped over the end of the electrode and heat bonded thereto, leaving exposed a centrally located contact 107.

Substantially identical mercury metering orifices 108 and 109 are provided in the wall of the sleeve 102, and are positioned above and below the level of the contact 107, the orifice 108 being adjacent to the shoulder 101, and the orifice 109 being adjacent to the glass seal 103. A relatively large opening 111 is also provided in the wall of the sleeve at approximately the level of the contact 107, all three of the above-mentioned openings being in the portion of the tube furthermost removed from the eccentrically positioned electrode 23.

When properly positioned within the switch the level of the mercury, with the displacer in its deenergized position, will be approximately at the level indicated by the line A, below the level of the contact 107, and preferably above the mercury metering orifice 108. In this position there is, of course, no electrical connection between the mercury and the electrode 23. When the coil is energized the displacer is drawn downwardly, causing the level of the mercury outside of the sleeve 102 to rise rapidly. The rise of the mercury within the sleeve is, however, governed in this case by the size of the mercury metering orifice 108, and will therefore rise more slowly, eventually reaching the level of the mercury outside of the sleeve, indicated by the line B, in which position the mercury is in electrical

connection with the contact 107. When the coil is deenergized the displacer rises, causing the mercury outside of the tube 102 to fall. This does not, however, break the contact between the electrode 23 and the mercury immediately, as the fall of the mercury within the sleeve 102 is delayed by the mercury metering orifice 108, through which the mercury slowly escapes.

Under the above described conditions it may be seen that this time delay element provides a delayed make and a delayed break, provided the high mercury level B is above the level of the contact 107 and below the lower margin of the relatively large opening 111. If desired, however, the switch may be adjusted to provide a quick make with a delayed break by causing the mercury to rise to the level designated by the line C, in which the mercury will immediately fill the sleeve 102 through the opening 111 when the displacer is energized, completing the circuit between the contact 107 and the mercury. In this instance, when the displacer is deenergized, the mercury metering orifice 108 delays the fall of mercury within the sleeve 102 in a manner similar to that previously described.

The amount of mercury displaced by movements of the displacer depends, of course, upon the depth to which the displacer is drawn, and the high level of the mercury may, therefore, be adjusted by varying the position of the air gap between the pole sleeves with respect to the displacer. The mercury may, therefore, be made to rise to either the level indicated by the line B, or that indicated by the line C, by adjusting the position of the switch within the coil; or, if desired, the high level of the mercury may be controlled by varying the amount of mercury added to the envelope.

Fig. 7 illustrates the time delay element shown in Fig. 6, in an inverted position. In this position there is normally electrical contact between the electrode 23 and the mercury when the displacer is in its deenergized position, the level of the mercury being normally at either the level indicated by the line D or that indicated by the line F. When the coil is energized the displacer is drawn upwardly, causing the mercury level outside of the sleeve 102 to fall rapidly. This action does not immediately break the electrical connection between the mercury and the contact 107, due to the action of the mercury metering orifice 108, which delays the passage of mercury out of the sleeve 102, thereby providing a delayed break. When the coil is deenergized the displacer falls to its normal position, causing the mercury level outside of the sleeve 102 to rise either to the level indicated by the line D or the level indicated by the line F. In the former case the mercury will immediately fill the sleeve 102 through the opening 111, providing a quick make. If, on the other hand, the mercury rises only to the level indicated by the line F, the element will provide a delayed make, as the mercury will rise slowly within the sleeve 102, due to the action of the mercury metering orifice 108.

It is desirable that in all cases the mercury metering orifices 108 and 109 be normally below the low mercury level, for in this position the surface tension effect of the mercury does not affect the flow through the orifice. If desired, the insulating members 104 and 106, lying within the sleeve 102, may be formed in the shape of cups to provide a mercury to mercury contact.

By incorporating my reversible time delay ele-

ment any one switch may be made to function in an upright position as a front contact switch having either a delayed make and a delayed break, or a quick make and a delayed break.

5 The same switch, in an inverted position, will also function as a back contact switch having a delayed make and a delayed break, or, if the normal mercury level be properly adjusted in the manufacturing process, will provide a quick make and a delayed break. Any one switch incorporating the above described time delay element will, therefore, provide any three of four distinct types of action without alteration of any of the component parts of the assembled switch.

10 15 It will be noted that the construction of the reversible time delay element illustrated in Figs. 5 and 7 is, in many respects, similar to the electrode cap described in connection with Figs. 1 and 2. It is therefore possible, by adjusting the diameter and position of the relatively large opening 111, the position of the air gap 47, and/or the height of the mercury fill, to provide a switch having the time delay functions hereinbefore described operating as a front contact switch in 20 either position, or as a back contact switch in 25 either position, the adjustments being similar to those described in connection with Fig. 1.

Specifically, if it is desired to provide a switch 30 incorporating a time delay function, and operating as a front contact switch in either position, the opening 111, corresponding to the opening 32 in Fig. 1, is positioned approximately midway within the switch envelope 11, and the level of the mercury adjusted to normally lie below the 35 level of the contact 107, as for example, the line designated A in Fig. 6, or at the level designated by the line E in Fig. 7. The switch envelope 11 is positioned with respect to the air gap 47 to draw the displacer downwardly into the mercury, causing the level of the mercury to rise to the level indicated by the line B or the line C in Fig. 6, or to the level indicated by the lines D or F in Fig. 7.

40 The same switch may be made to function as a back contact switch in either position by locating the opening 111 approximately midway within the envelope, and providing a normal mercury level at approximately the levels indicated by the lines C or D in Fig. 6, or the lines D or F in Fig. 7. If the switch is to function as a back contact 45 switch, the position of the air gap must always be above the displacer, so that energization of the coil 43 will cause the displacer to rise out of the mercury, thereby lowering the mercury to a level such as that indicated by the line A in Fig. 6 or the line E in Fig. 7, these levels in both instances being below the level of the contact 107. In either case, the displacement of the electrode assembly and insulating sleeve 24 may be compensated by increasing the volume of the glass seal 103, or by other suitable means.

50 If, as previously described, the switch is to operate as a front contact switch in one position, and as a back contact when inverted, the opening 111 is positioned to lie above the normal mercury level in one position, and below the mercury level 55 when inverted.

Due to its simple and efficient construction, my switch is capable of operating on extremely low exciting currents, and as it has very low contact resistance it is efficient in operation. The materials from which the switch is manufactured are not subject to break-down under excessive loads, and are strong and durable, thereby increasing both the safety and durability of the switch. The 60 preferred metals for envelope 11 have an electri-

cal resistance about forty times that of copper, and there is no danger that, with an alternating exciting current, eddy currents will be set up in the envelope of sufficient value to require an objectionably higher exciting current. Likewise, when direct current is used there will be no objectionable lag in the deenergization upon opening the energizing circuit. The high strength and impervious nature of the metal switch envelope permits the advantageous use of a high pressure gas fill which cannot, of course, be safely used in conjunction with the conventional type of glass switch envelope. One reason for the preference for the 16-8 type of steels is that the walls, when polished, may be relatively thin and still be impervious. The high strength and impermeability of the metal switch envelope permits the advantageous use of a high pressure gas fill which cannot, of course, be safely used in conjunction with the conventional type of glass switch envelope, and by use of the type of cap described in connection with Fig. 3 the operating characteristics of the switch may be adjusted after assembly without damage to the switch envelope.

The joint formed between the switch envelope and the cap or base will retain the high gas pressures within the switch indefinitely, and is particularly efficient in this respect when compared to similar joints in other types of switches employing rubber or other organic materials as a sealing medium.

The foregoing description has been by way of illustration only, and it is to be understood that the specific embodiments herein described are merely examples of the many ways in which my invention may be embodied within the scope of the appended claims. The claims, therefore, are to be construed as broadly as the prior art will permit.

I claim as my invention:

1. A mercury switch assembly including an envelope, a quantity of mercury within the envelope, an electrode at times completing a circuit through the mercury, and magnetically responsive means within the envelope adapted to be actuated by means external of the envelope for changing the condition of the electrical circuit through the mercury, characterized by the formation of the envelope of at least two metal parts substantially in contact with one another along a line of junction, both of said parts resisting wetting by mercury whereby the flow of the mercury between the parts at the line of junction is prevented.

2. A mercury switch assembly including an envelope, a quantity of mercury within the envelope, an electrode at times completing a circuit through the mercury, magnetically responsive means within the envelope adapted to be actuated by means external of the envelope for changing the condition of the electrical circuit through the mercury, characterized by the formation of the envelope of at least two metal parts substantially in contact with one another along a line of junction, both of said parts resisting wetting by mercury whereby the flow of the mercury between the parts at the line of junction is prevented, and a seal along the line of junction comprising a metal, which will amalgamate with mercury, fused to the parts along the line of junction but externally thereof in a position in which the mercury cannot penetrate.

3. A mercury switch assembly including an envelope, a quantity of mercury within the envelope, an electrode at times completing a circuit through the mercury and magnetically responsive means

within the envelope adapted to be actuated by means external of the envelope for changing the condition of the electrical circuit through the mercury characterized by the formation of the envelope of at least two metal parts substantially in contact with one another along a line of junction, and the provision of a hermetic seal along said line on the outside of the envelope formed of a material which is deleteriously affected by mercury, one of said metal parts being resistant to wetting by mercury whereby the flow of mercury between the parts at the line of junction is prevented.

4. A mercury switch assembly including a metal switch envelope having an integrally formed seat at one end, a mercury fill, a metal plate having an aperture and an electrode assembly including an electrode and an insulating sleeve sealed through the aperture, the metal plate having a thickness less than the depth of the seat and adapted to be received by the seat whereby the metal plate may be sealed to the envelope by turning the extending ends of the envelope inwardly against the external surface of the metal plate.

5. In a mercury switch relay, a coil, a non-magnetic metal switch envelope associated with said coil and closed at one end by an electrode assembly comprising a plate of magnetic material through which an electrode is hermetically sealed, contact means and a mercury fill within the envelope, a magnetically responsive displacer for shifting the level of the mercury fill, and spacing means within the envelope for preventing magnetic adherence of the displacer to the magnetic metal plate.

6. For use in a mercury switch, a metal switch envelope having an open end, said open end having an internal shoulder, a metal cap adapted to rest upon said internal shoulder, and means for sealing said metal cap to the envelope, said means including metal all along the seam therebetween in the intimate contact resulting from its application as a molten metal.

7. A mercury switch of the displacer type having predetermined operating characteristics formed by joining prefabricated sub-units, said sub-units comprising a non-magnetic metal switch envelope, and an electrode assembly comprising a metal base, an electrode and an insulating sleeve sealed to said base and electrode.

8. A mercury switch of the displacer type having predetermined operating characteristics formed by joining together prefabricated sub-units, said prefabricated sub-units comprising a non-magnetic metal switch envelope and an electrode assembly comprising a metal base having an opening, an electrode, and an insulating sleeve heat bonded to said electrode, said insulating sleeve being positioned within said opening and sealed to said metal plate.

9. A mercury switch of the displacer type having predetermined operating characteristics formed by joining together prefabricated sub-units without fusion, said prefabricated sub-units comprising a non-magnetic metal switch envelope, a quantity of inert gas within said envelope exerting a pressure substantially in excess of atmospheric pressure, a quantity of mercury within said envelope, and an electrode assembly comprising a metal base having an opening therein, and an electrode having an insulating sleeve bonded thereto, said electrode and insulating sleeve being positioned within said open-

ing and said insulating sleeve being sealed to said metal plate.

10. A mercury switch assembly including a metal switch envelope having an internal annular seat formed at one end, a mercury fill, a metal closure cap having an aperture therethrough, an electrode hermetically sealed through the aperture and insulated therefrom, the outer margin of the metal cap having a thickness less than the depth of the seat and adapted to be received by the seat whereby the metal cap may be sealed to the envelope by causing the extending ends of the envelope to overlay the adjacent external surface of the cap.

11. In a mercury switch relay, a coil, a non-magnetic metal switch envelope associated with said coil and closed at one end by an electrode assembly comprising a plate of magnetic material through which an electrode is hermetically sealed, contact means and a mercury fill within the envelope, a magnetically responsive displacer for shifting the level of the mercury fill, and spacing means within the envelope for preventing magnetic adherence of the displacer to the magnetic metal plate, said spacing means comprising a stop of non-magnetic material projecting beyond the end of the displacer and establishing a minimum air gap between the magnetic displacer and the magnetic plate.

12. In a mercury switch, the combination of a metal switch envelope formed of non-magnetic tubing, an electrode assembly adapted to close one end of the envelope and comprising a cap having an electrode extending therethrough and hermetically sealed to the cap, a mercury fill, a magnetically responsive displacer for shifting the mercury fill to actuate the switch, and a cap closing the other end of the envelope, and means for hermetically sealing the junction between the envelope and the top and bottom caps. 40

13. The method of fabricating a metal envelope mercury switch comprising taking a metal envelope having an opening at one end thereof, closing said opening with a metal cap fitted into the opening and having its side wall in close 45

proximity to the adjacent wall of the envelope but leaving an infinitesimal annular space therebetween, at least one of the metal parts being resistant to wetting by mercury, exteriorly sealing the mating walls of the envelope and cap with a substance that amalgamates with mercury, and then introducing a mercury fill and high pressure gas fill into the envelope, but subjecting at least a portion of the annular space to the high pressure gas fill before permitting it to be covered by mercury at said high pressure whereby a high pressure gas pocket is formed in the annular space which together with the non-wetting characteristic of said one metal part effectively prevents mercury from permeating the annular space to reach the sealing substance.

14. The method of fabricating a metal envelope mercury switch which comprises taking a metal envelope open at both ends, closing one end of the envelope with a metal cap and sealing the annular space between the envelope and the cap with a material that amalgamates with mercury, and then introducing a mercury fill and high pressure gas fill into the envelope but subjecting at least a portion of the annular space to the high pressure gas fill before permitting it to be covered by mercury at said high pressure, whereby a high pressure gas pocket is formed in the annular space which effectively prevents mercury from permeating the annular space to reach the sealing material.
